FUSE DEVICE

Application filed June 30, 1928. Serial No. 289,604.

The present invention relates to devices in which fuses are housed within receptacles into which new fuses are adapted to be placed after the blowing of fuses originally present. 5 The object of the present invention is to produce a novel device of this kind comprising a few simple parts that may be quickly and easily assembled or taken apart.

The various features of novelty whereby 10 our invention is characterized will herein-after be pointed out with particularity in the claim; but, for a full understanding of our invention and of its objects and advantages, reference may be had to the following detailed description taken in connection with the accompanying drawing, wherein:

Figure 1 is an elevation of a device arranged in accordance with our invention, one of the terminal caps being shown in section; 20 Figs. 2 and 3 are side elevations of the two body members of the structure separated from each other; Fig. 4 is a bottom view of the element shown in Fig. 2, whereas Fig. 5 is a top view of the element shown in Fig. 3; 25 Fig. 6 is a longitudinal section through the device ready for use; Fig. 7 is an end view of the device with the terminal cap removed; Fig. 8 is a section taken on line 8-8 of Fig. 6; and Fig. 9 is a plan view of the fuse 30 strip.

Our improved device comprises a hollow body member or casing of insulating material between which is held a fuse exposed at the ends of the casing, together with terminal members adapted to fit over the ends 35 of the casing to hold the sections together and at the same time make good contact with the ends of the fuse.

In the arrangement shown, the casing is 40 made in two sections 1 and 2 which, when laid together, form a cylinder. The main central portion of each of the two sections is preferably semi-cylindrical in form, hollowed out on the flat side so that when the two 45 sections are placed together, as shown in Fig. 6, there is formed between them a chamber 3 of considerable size. In order to produce a tight joint between the two sections when they are laid together, one of them is 50 preferably provided in its flat side with an

endless groove 4 surrounding the cavity, while the other has a projecting ledge or rib 5 adapted to fit into the groove. Gases or other fluids, in order to pass between the chamber in the casing and the exterior, 55 through the sides of the casing, must therefore travel through the grooves and around the ledges or ribs.

The two ends of one of the members, conveniently the member 1, are made cylindrical, 60 as indicated at 6, 6 to permit the combined terminals and clamps to be placed over the same. A deep wide groove 7, extending longitudinally of the casing, is cut through each of the cylindrical end portions. The 65 member 2 is provided at its ends with tongues 8, 8 adapted to fit into the grooves in the other section when the two sections are laid together.

The fuse may be in the form of a strip 9 70 adapted to be laid on the member 1 with its ends projecting out through the grooves 7; the fuse being long enough to permit the extreme end portions 10, 10 to be bent down to overlap the end faces of the member 1. 75

The cylindrical parts of the member 1 are preferably provided with external screw-threads, indicated at 11, and the terminals are preferably in the form of cups 12 screw-threaded internally. When the cup-shaped 80 terminals are screwed in place, they clamp the two halves or sections of the casing firmly together and at the same time make good contact with the turned over ends 10 of the fuse. The parts are preferably so proportioned 85 that the portions of the fuse lying in the grooves are pressed down firmly by the overlying tongues, so that the fuse will be held against twisting when the terminals are applied. 90

When a fuse blows it is desirable that the fumes be allowed to escape. To this end, we have provided a second set of grooves, 13, cut down through the bottom of the grooves 7, 95 each groove 13 extending from one end of the casing to the main cavity 14 in the member 1. Furthermore, the bottom of each terminal cup is provided with a hole 15 through the same. Consequently when a fuse blows, the

fumes may escape through the grooves 13 and 7 through the holes 15.

After a fuse has blown, the device may be lifted from the clips in which it is set, by grasping the body of insulating material lying between the two terminals. Then, in order to renew the fuse, the cup-shaped terminals need only be unscrewed, whereupon the sections of the casing may be separated from each other to permit a new fuse to be inserted. Then, when the terminals are again screwed in place, the device is ready for use.

The fuse is sufficiently frail to enable the pressure of the fumes, upon blowing, to burst through the thin end portions and escape through the holes 15 in the bottoms of the terminals. Normally, however, the ends of the casing are sealed by reason of the fact that the end portions 10 of the fuse are held over the ends of the grooves 13 by the terminal members.

While we have illustrated and described with particularity only a single preferred form of our invention, we do not desire to be limited to the exact structural details thus illustrated and described; but intend to cover all forms and arrangements which come within the definitions of the invention constituting the appended claim.

We claim:—

A container for a fuse comprising two semi-cylindrical pieces of insulating material, the ends of one piece being in the shape of externally screwthreaded cylinders each having a deep longitudinal notch extending throughout the length thereof in one side, the other piece having at the ends tongues fitting into said notches, the meeting faces of said pieces being shaped to produce a central closed chamber and seats for a fuse extending from said chamber to the ends of the container underneath said tongues, and metal caps screwed upon said cylindrical ends to hold said pieces together and engage the ends of a fuse strip extending lengthwise between said pieces.

In testimony whereof, we sign this specification.

ERNST G. K. ANDERSON.
